CLAIM

The ornamental design for a vaporizer cartridge, as shown and described.

DESCRIPTION

FIG. 1 is a perspective view of the vaporizer cartridge; FIG. 2 is a top plan view of the vaporizer cartridge of FIG. 1, with the bottom plan and right side elevational views being the same as the top plan view of FIG. 2, and the left side elevational view being a mirror image of the top plan view of FIG. 2;

FIG. 3 is a front elevational view of the vaporizer cartridge of FIG. 1; and,

FIG. 4 is a rear elevational view of the vaporizer cartridge of FIG. 1.

The broken lines in the drawings illustrate portions of the vaporizer cartridge that form no part of the claimed design.
